CALCULATING MACHINE

John L. Moody, Oakland, Calif., assignor to
Friden Calculating Machine Co., Inc., a corpora-
tion of California

Application April 20, 1942, Serial No. 439,644

5 Claims. (Cl. 235—144)

This invention relates to calculating machines and is concerned more particularly with the provision of an improved register construction and resetting mechanism therefore to facilitate calculations such as payroll work.

In many calculations, for example in payroll work, it is desirable to multiply the rate paid for the work by the number of hours of work to obtain the amount to be paid each employee. It is also desirable simultaneously to provide a total of the amount paid the various employees in a particular department, to provide a correct total of the payroll in such department. In each type of calculation it is desirable to complete the calculation to the nearest half-cent and to perform this completion in such a way that the payroll total will be correct, that is, each individual calculation in the total will be performed to the nearest half-cent.

It is a general object of the invention, therefore, to provide improved means for making payroll calculations.

Another object of the invention is to provide a calculating machine in which the resetting operation serves to enter one or more half-cent values at desired orders in the accumulator.

Another object of the invention is to provide a resetting mechanism which will enter values in the accumulator as a part of the resetting operation.

Another object of the invention is to provide a calculating machine for attaining the foregoing objects and provides a simple, inexpensive construction.

Other objects and advantages of the invention will be apparent from the following description of a preferred embodiment as illustrated in the accompanying drawings, in which:

Figure 1 is a plan view of a calculating machine embodying the features of the invention;

Figure 2 is a plan view of the register carriage, with the cover removed to illustrate the details of construction;

Figure 3 is a rear view of the right hand end of the carriage as viewed in Figure 2;

Figure 4 is a vertical sectional view taken as indicated by the line 4—4 in Figure 2;

Figure 5 is a sectional view taken along the line 5—5 of Figure 4;

Figure 6 is a rear view of the left end of the carriage as viewed in Figure 2;

Figure 7 is a vertical sectional view taken as indicated by the line 7—7 in Figure 6;

Figure 8 is a sectional detailed plan taken as

indicated by the line 8—8 in Figure 6, with certain parts omitted;

Figure 9 is a perspective view of the resetting rack and associated parts;

5 Figure 10 is a schematic plan view of the half cent mechanism associated with the numeral wheel, the view being indicated by the line 10—10 of Figure 4;

Figure 11 is a schematic plan view similar to Figure 10 showing the parts at the middle of a resetting operation;

10 Figure 12 is a schematic plan view similar to Figures 10 and 11 but showing the parts at the end of a resetting operation in which the half cent mechanism has been active;

15 Figure 13 is a schematic plan view of a portion of the half-cent mechanism, the view corresponding to the position of the parts shown in Figure 10 and taken along the line 13—13 of Figure 4;

20 Figure 14 is a view similar to Figure 13 with the parts corresponding to the position shown in Figure 11;

25 Figure 15 is a view similar to Figures 13 and 14 with the parts positioned similarly to Figure 12.

The invention is illustrated as embodied in the type of calculating machine disclosed in the patent to Carl M. Friden, 2,229,889, dated January 28, 1941, as modified in the copending applications of Carl M. Friden, Ser. No. 240,269, filed November 14, 1938, and Carl M. Friden and Anthony B. Machado, Serial No. 348,966, filed July 31, 1940.

Generally, such calculating machines include drive means and actuating means whereby adding, subtracting, multiplying and dividing operations can be carried on with respect to an accumulator mounted in a shiftable carriage. Figure 1 shows a calculating machine having a body 20 on which a register carriage 21 is mounted for endwise shifting movement. The machine is provided with conventional selecting and actuating mechanism controlled during calculating operations by numeral keys 11 and plus and minus keys 12 and 13 in the usual fashion.

20 Clear key 14 is provided for controlling release of depressed numeral keys. Suitable mechanism including shift keys 16 and 17 is provided for shifting the carriage from order to order. Key 18 controls suitable means for causing resetting of the accumulator by power drive means. The above mechanisms are generally conventional and their disclosure is not necessary to an understanding of the instant invention; and for that reason only the shiftable register carriage has

25 been disclosed in this application.

Referring to Figure 2, a shiftable register carriage indicated generally at 21 includes the carriage frame 22 and the transverse bar 23 supported in spaced relation on the frame 22 by similar end plates 24, only one of which is shown. The carriage provides a mounting for the numeral wheels or dials 26 of the accumulator and 27 of the revolutions counter.

Referring to Figures 2 and 4, each numeral wheel 26 is carried by a numeral wheel shaft 28 which is suitably journaled between the opposed halves of the carriage frame 22. At its lower end the numeral wheel shaft 28 carries a ten tooth gear 29 by means of which values can be introduced into the accumulator as disclosed in said patent. The alignment of the desired figure on the numeral wheel dial with the sight opening 30 (Figure 1) in the cover 31 of the carriage is maintained by a suitable centralizing means including a ratchet tooth gear 32 (Figure 4) mounted on numeral wheel shaft 28 cooperating with a spring pressed ball 33. This mechanism is conventional.

To enable resetting of the dials 26 of the accumulator, each shaft 28 carries a resetting gear 34 (Figures 4 and 7) with alternate gears 34 offset axially along their shafts 28. Each gear 34 is mutilated as seen in Figure 13 for example, and the mutilated portion is in the position shown in Figure 13 with the associated dial standing at zero.

To perform the resetting operation in connection with the gears 34 of the dials 26 a resetting rack is provided as shown in Figures 4 and 9 having spaced alternately vertically offset gear racks 36 formed on parallel bars 37 and 37a of the racks which are secured in spaced relation by suitable spacers and studs 39. Each rack 36 has a cutaway portion 41 at one side thereof and a raised portion 42 at the other side thereof. As seen in Figure 9, the resetting rack is split with a right-hand portion 37, 37a and a left-hand portion 38, 38a. The right-hand section 37, 37a is associated with the eight lowest order dials 26 while the left-hand section 38, 38a is associated with all dials of higher order.

As seen in Figure 4, the resetting rack is mounted for endwise movement in the carriage frame past the resetting gears 34 of the associated dial, and when moved endwise from the position shown in Figure 2 for example, will serve to rotate any dials which are displaced at zero by engagement with their resetting gears 34 until the mutilated portions of the resetting gears are aligned with the resetting rack when the drive will cease. In order to insure stopping of the numeral wheels or dials at zero without overthrow, a stop slide 46 (Figures 2, 4 and 10) is mounted upon the upper surface of the carriage frame 22 having a tooth 47 for engagement with a stop ear 48 carried by the dial shaft 28 during the resetting operation. The slide 46 is normally held inactive in the position shown in Figures 6 and 10 by a spring 49, and is temporarily moved to active position during a resetting operation as later described.

To operate the resetting rack 37, a post 51 (Figures 2, 3 and 9) is provided having a sleeve 52 mounted thereon carrying an adjustable handle 53. Sleeve 52 (Figure 2) carries an arm 54 for engagement with a pin 56 carried by an operating slide 57 slidably mounted for endwise movement on the carriage frame. The slide 57 is operable by power operated means of the character 78

disclosed in said application, Serial No. 240,269, or is operated manually when the handle 53 is moved to the right as viewed in Figure 2 because of the engagement of part 51 with overlapping end portion 57a of the slide 57.

To operate the stop slide 46 during resetting, the slide 57 has a pin 58 (Figures 2 and 10) which lies in front of the cam surface 59 of the bell-crank 61 pivoted at 62 on the carriage frame and having a pin and slot connection at 63 with the slide 46.

As previously explained, the resetting rack 37 is associated only with a lower order group of numeral wheels or dials so that operation of handle 53 15 always operates to reset the lowermost eight dials of the accumulator. The higher order dials can be selectively coupled for simultaneous resetting operation with the lower eight dials. As seen in Figures 6 to 8, the resetting rack 38 associated 20 with the higher order group of dials is provided with a laterally extending arm 66 which extends through an aperture in the carriage frame and is provided with an upstanding ear 67. A bracket 65 fixed to frame 22 carries a post 68 having a transverse pin 69 therein and receiving a sleeve 71 provided with a disc 72 having transversely aligned seats for the pin 69. Sleeve 71 is spring urged downwardly by spring 73 held in place by operating handle 74 and a suitable retaining screw. The ear 67 of arm 66 (Figures 6 to 8) is 25 adapted for engagement by hook 76 adjustably pivoted at 77 on an extension of slide 57 and urged by spring 78 against a stop pin 79. As seen in Figures 6 and 7, tooth 81 of hook 76 is engaged with ear 67 so that the resetting rack 38 30 will be moved upon operation of slide 57. As seen most clearly in Figure 8, disc 72 carries a cam extension 82 which is adapted to be swung from the full line position shown in Figure 8 to the dotted line position where it will engage the camming surface provided by the back face of tooth 81 to lift the hook 76 and tooth 81 above the ear 67. In this lifted position of tooth 81, endwise movement of slide 57 is ineffective to move the resetting 35 rack 38 with the rack 37. Thus, if the handle 74 is adjusted to position cam extension 82 as shown in dotted lines in Figure 8, resetting of the lowermost eight orders only of the accumulator will occur.

As previously stated, in payroll work it is desirable to enter half cents to "round off" values of a payroll computation to the nearest cent. Two such mechanisms are provided for selective operation as disclosed herein, one of those being 55 associated with the number 2 dial, while the other is associated with the number 8 dial, i. e., the highest order dial operated on by the resetting rack 37. The two half-cent mechanisms are similar and only one will be described in detail.

To provide for selective entry of an automatic half-cent, means are provided for selectively causing the resetting rack to return a selected dial to its "5" position rather than to its "0" position. As seen in Figures 4 and 5, the dial shaft 28 of 60 the number 2 dial is provided with a tooth 91 which is centrally located with respect to the cut-away portion of the resetting gear 34 to be facing the resetting rack 37 in the "0" position of the dial. The resetting rack 37 has an actuating pawl 92 pivoted on its bottom surface at 93 and having a tooth 94 for engaging the tooth 91 during the return movement of the rack 37. Pawl 92 is biased to place the tooth 94 active by spring 96 connected between an ear of pawl 92 and an ear 65 97 on rack 37. Pin 98 on rack 37 engages an aper-

tured portion of pawl 92 to provide a stop. With the parts shown as positioned in Figures 5 and 13, movement of the rack 37 to the right will cause gear teeth 36 thereof to engage gear 34 if the associated dial is out of its zero position and turn the dial to zero during movement of the rack to the right as viewed in Figure 13. During this movement, the pawl 92 yields as it passes over the tooth 91. Figure 14 shows the parts at the end of the travel of rack 37 to the right. During 10 return movement of rack 37 under the influence of its spring, tooth 94 will engage single tooth 91 and cause the gear 34 to mesh with the gear teeth 36 at a time so that the gear teeth 36 will rotate gear 34 and the associated dial to its five position 15 as shown in Figure 15.

Means are provided for preventing overthrow of the dial when it is adjusted to its five position.

Referring to Figures 4 and 10, an overthrow preventing pawl 101 is pivoted on stud 102 mounted on the carriage frame and extending through a slot in the stop slide 46. Pawl 101 is connected by a spring 103 with a stud 104 on stop slide 46 so that upon movement of slide 46 to the right from the position shown in Figure 10 to that shown in Figure 11, pawl 101 is oscillated clockwise as viewed in Figure 10 to the position shown in Figure 11 for engagement with a stop tooth 106 of disc 105 on dial shaft 28. Stop tooth 106 corresponds to the "5" position of the associated dial. It will be noted that stop slide 46 is maintained active throughout the greater part of the return stroke of the resetting rack because the pin 58 as seen in Figure 11 at the end of its stroke to the right lies against a straight portion of the bellcrank 61.

To prevent rebound of the dial in the opposite direction, the slide 46 (Figure 10) has pivoted thereon at 107 a stop pawl 108 urged against the stop pin 109 by a spring 111. Pawl 108 has a flat surface 112 for engagement with a cooperating flat surface 113 of disc 105 carrying tooth 106. As seen in Figure 11, with the stop slide 46 moved to the right, pawl 101 and pawl 108 are both urged to active position, pawl 108 yielding however to permit movement of tooth 106 past the same during the setting to the "5" position. Figure 12 shows the position of the parts after a resetting operation to "5" and the stop slide 46 has moved back under the influence of its spring so that pawls 101 and 108 are both free of the disc 105.

To provide for selective operation of the automatic half cent mechanism, pawl 92 has an arm 116 (Figures 3, 4 and 13) having a cam nose for engagement with the lower end of a settable control element 117 which is mounted for sliding movement on the carriage frame 22 by bracket 118. In the raised position of control element 117 shown in Figure 4, the automatic half-cent mechanism is operative. However, if the settable element 117 is moved downwardly so that it is latched in its lower position by the engagement of spring pressed ball 119 with the uppermost of its associated locating grooves, its lower

end will lie in the path of the cam nose of arm 116 of pawl 92 so that the pawl will be rocked counterclockwise as viewed in Figure 13 to move tooth 94 out of the path of tooth 91. With this condition of the parts, the numeral wheel or dial having the automatic half-cent mechanism will be restored to zero during each operation.

As seen in Figures 1 and 2, a second half-cent mechanism is provided at the eighth order dial under control of settable element 117a.

I claim:

1. In a calculating machine having a register comprising a series of numeral wheels, resetting mechanism for said wheels including a rack having a set of teeth for each of said wheels, said rack being operative upon movement in one direction to restore said wheels to zero, and means for causing driving movement of a numeral wheel by said rack during its return movement.

2. In a calculating machine, a numeral wheel having a mutilated gear thereon, a rack mounted for back and forth movement relative to said wheel and engageable with said gear in one direction of movement to move said wheel to a predetermined position thereof if displaced therefrom, and selectively operable means for causing engagement of said rack and said gear during movement of said rack in the other direction.

3. In a calculating machine, a numeral wheel having a mutilated gear thereon, a rack mounted for back and forth movement relative to said wheel and engageable with said gear in one direction to move said wheel to a predetermined position thereof if displaced therefrom, and means carried by said rack for turning said wheel during movement of said rack in said other direction to cause engagement of said rack and said gear.

4. In a calculating machine, a numeral wheel having a mutilated gear thereon, a rack mounted for back and forth movement relative to said wheel and engageable with said gear in one direction of movement to move said wheel to a predetermined position thereof if displaced therefrom, means carried by said rack and spring urged to active position for turning said wheel during movement of said rack in said other direction to cause engagement of said rack and said gear, and a settable control element for moving said spring-urged means to inactive position.

5. In a calculating machine, a register comprising a series of numeral wheels, means for resetting said wheels to "zero" position including a resetting member moved from an initial position to perform the resetting operation and returned to said initial position at the conclusion of the resetting operation, and means for setting one of said numeral wheels to a predetermined position other than "zero" comprising a device for causing transmission of movement from said resetting member to said numeral wheel during return of said resetting member to said initial position.

JOHN L. MOODY.
